UNITED STATES PATENT OFFICE.

WILLIAM E. BECKWITH, OF RICHMOND, VIRGINIA, ASSIGNOR TO THE A. S. KRATZ COMPANY, INC., OF RICHMOND, VIRGINIA, A CORPORATION OF VIRGINIA.

BOX.

1,277,833.

Specification of Letters Patent. Patented Sept. 3, 1918.

Application filed April 18, 1918. Serial No. 229,295.

To all whom it may concern:

Be it known that I, WILLIAM E. BECKWITH, a citizen of the United States of America, and a resident of Richmond, county of 5 Chesterfield, and State of Virginia, have invented certain new and useful Improvements in Boxes, of which the following is a full and clear specification.

The object of this invention is to provide 10 an inexpensive box for holding tobacco, etc., the construction being such that the contents of the box may be readily shaken or poured out through a discharge opening formed in the main flap at one end of the box, this discharge opening being adapted to be covered by a supplemental flap, which latter may be opened and the contents of the box discharged.

In the drawing—

20 Figure 1 is a perspective view of a closed box;

Fig. 2 is a similar view showing the supplemental flap open thus enabling the contents of the box to be shaken or poured out 25 through the discharge opening;

Fig. 3 is a vertical sectional view showing the parts in the position shown in Fig. 2; and

Fig. 4 is a perspective view of a blank partly folded.

30 In the drawing, the box *a* is made of a blank paper-board scored and folded and pasted substantially in accordance with the usual method. The lower end of the box is permanently closed by the usual arrangement of flaps. The upper or dispensing-end 35 of the box is provided with the usual end flaps *b* and the usual side flaps *c*, which are adapted to be folded and tucked into the box in the usual way, as shown in Fig. 2; that 40 is, end flaps *b* are first folded in and then the main flap *c* (being scored at *d* and *e*) is folded over and cross the top of the box and has its free end *f* tucked down in the end of the box against the outer wall.

45 At the side of the box opposite the side to which the main flap *c* is hinged, I extend the side wall of the box to form a supplemental flap *g* which is scored at *h* to enable the free end *i* of this flap to be readily 50 tucked down into the box in position to lie

against the opposite wall, as shown in Fig. 3, slit *j* being provided in the main flap to enable this to be done. The opening *j* is a slit rather than a slot, so that it will to a certain extent exert a clamping action on 55 the inserted end *i* of the flap, and this slit *j* is formed coincident with the top edge of the side wall of the box, so that the inserted end *i* will lie close against the inner face of the wall of the box opposite the free end *f* 60 of the main flap. In the main flap is formed a discharging opening *k*, this opening being in transverse alinement with the flap *g* so as to be covered by the flap when the flap is tucked in. This opening is in the form of a 65 semi-circle, its straight edge extending lengthwise of the top of the box and approximately in the center of the top wall. Its curved edge extends to the edge of the top at a point adjacent the hinge-connection 70 of the flap *g*, so that when discharging the contents of the box through this opening, the outward movement of the contents will be unobstructed.

It will be observed that a feature of importance lies in forming the discharge opening *k* in the main flap and in providing a supplemental flap hinged to the box at a point opposite the hinge of the main flap, whereby when the supplemental flap is 80 folded over upon the main flap, it will cover the discharge opening and will reinforce and strengthen the main flap. When the box is used for packaging smoking tobacco for the retail trade, it will be observed that 85 the revenue stamp may be readily applied so as to seal the supplemental flap in its locked or closed position, so that the discharge opening cannot be uncovered without disturbing the stamp. 90

The nature and scope of the invention having been thus indicated and its preferred embodiment having been specifically described, what is claimed as new is:

A box of the character described having 95 a flap hinged to one of the upper edges of the box and provided with a slit extending along the edge-fold forming the hinge and also with a dispensing opening located at a point between said slit and the free edge of 100

the flap, said flap being folded along a line between said opening and its free edge to enable it to be tucked down into the box along the vertical wall opposite the slit, and 5 another flap hinged to the top edge of the wall opposite said slit and adapted to extend across and cover the dispensing open-

ing and to have its free edge tucked down vertically into said slit and lie against the adjacent vertical wall of the box. 10

In testimony whereof I hereunto affix my signature.

WILLIAM E. BECKWITH.
